UNITED STATES PATENT OFFICE.

JAMES A. W. SEARS, OF CHATTANOOGA, TENNESSEE, ASSIGNOR OF ONE-HALF TO W. F. STEPHENS AND (MRS.) MARY A. STEPHENS, BOTH OF CHATTANOOGA, TENNESSEE.

CHAIR.

1,026,706.

Specification of Letters Patent.

Patented May 21, 1912.

Application filed January 20, 1912. Serial No. 672,287.

To all whom it may concern:

Be it known that I, JAMES A. W. SEARS, a citizen of the United States, residing at Chattanooga, in the county of Hamilton 5 and State of Tennessee, have invented certain new and useful Improvements in Chairs; and I do hereby declare the following to be a full, clear, and exact description of the invention, such as will enable others 10 skilled in the art to which it appertains to make and use the same.

This invention relates to chairs and more particularly to a combination chair.

An object of the invention is to provide a 15 chair which may be employed either as a parlor chair, reclining chair or as a hair dressing chair.

An object of the invention is to provide a 20 chair having a back and arms so constructed as to conceal mirrors and toilet articles such as combs, brushes, hair pins, etc.

Another object is to provide a chair of 25 this character, one arm of which may be so constructed as to allow a portion of the same, carrying a disappearing mirror to be swung to a position in front of the chair, said portion also carrying a folding shelf.

Another object is to provide a chair of 30 this character which may have the sides and back provided with lids or covers which may either be folded outwardly to form shelves or closed over the back and arms to give a finished appearance to the chair 35 when the same is to be used as a parlor chair.

Other objects and advantages will be hereinafter referred to and more particularly pointed out in the specification.

In the accompanying drawings which are 40 made a part of this application, Figure 1 is a perspective view of the chair with parts in position for use as a hair dressing chair. Fig. 2 is a vertical sectional view through the mirror and shelf carrying portion of 45 one arm, with the mirror concealed in this portion. Fig. 3 is a fragmentary perspective view of the upper portion of the other arm, and, Fig. 4 is a fragmentary cross sectional view through the lower portion of 50 the chair with its parts arranged as shown in Fig. 1.

Referring more particularly to the drawings in which similar reference numerals 55 designate corresponding parts in the several views, 1 represents the seat and 2 the

back of the chair. It will be understood that the seat and back may be of any form desired and may be upholstered or finished in any preferred manner.

The back carries any suitable pocket to 60 receive the U-shape mirror support 3, the opposite arms of which project upwardly, while the connecting or horizontal portion is adapted to rest in the bottom of the pocket when the mirror 4 is within the 65 pocket. The mirror 4 is mounted in a suitable frame 5 which is pivoted at opposite points to the upper ends of the parallel arms of the U-shape member 3 to support the mirror and frame between said arms. 70 The frame 5 is provided with suitable lifting straps 6 by means of which the mirror may be withdrawn from the pocket to its position shown in Fig. 1 to allow said mirror to be swung at various angles between 75 the arms of the U-shape mirror supporting member 3. The supporting member 3 is held in its upper-most position by means of the latch springs 7 secured to the parallel arms and adapted for engagement against 80 the top of the chair back 2 to prevent the supporting frame 3 from dropping back into the mirror pocket until the latch springs 7 are pressed against the arms to which they are secured. Each latch spring 85 7 has its upper end secured to an arm of the supporting frame 3 while its lower portion is bent outwardly and the lower extremity again bent toward the arm to be pressed into a slot provided therefor in 90 said arm to allow the frame 3 to move downwardly into the mirror pocket. When the supporting frame 3 and mirror frame 95 5 are within the pocket provided therefor in the chair back, they may be hidden from view by a lid or cover 8 hinged to the upper edge of the chair back and adapted to be folded over the latter to cover the mouth of the mirror pocket.

One arm 9 has its upper portion hollowed out to provide the pocket 10 within which may be stored toilet articles such as combs, brushes and hair pins and a lid 11 is hinged to the outer edge of said arm to be folded over the latter to cover the mouth of the 100 pocket 10 or to be folded outwardly to form a shelf and open the pocket 10, as will be clearly understood. The lower portion of the arm 9 may be finished in any preferred manner and provided with casters at each 105 110

end. The opposite arm 12 is provided with the vertical posts 13 and 14 at its rear and forward vertical edges respectively, connected by a horizontal board 15, upon which 5 the finished cover or outer surface 16 of said arm is secured. Hinged to the forward post 14 is the swinging bracket 17 which is also hinged at an opposite edge to the mirror carrying member 18 which is adapted 10 to be positioned in front of the chair and held in a forward position by the swinging bracket 17.

The swinging bracket 17 and mirror carrying member 18 are adapted to be 15 folded into the arm 12 between the standards 13 and 14 and beneath the connecting board 15 and held in position by the turn buttons 19 carried by the standards 13 and 14. The mirror carrying member 18 may 20 be readily handled and withdrawn from the arm 12 and placed in position in front of the seat 1 of the chair, by means of the hand holds 20 carried upon the outer face of said member. The member may also be 25 readily rolled upon the casters 21, carried thereby, to its various positions.

Within the mirror carrying member 18 is the U-shape mirror supporting bracket 22, the upwardly extending parallel arms of 30 which support a mirror carrying frame 23 therebetween, said frame being pivoted to the parallel arms of the supporting member 3 to allow the mirror to be swung at various angles. The frame 23 also carries 35 lifting straps 24 similar to the straps 6 carried by the mirror frame 5 and the arms of the mirror frame supporting member 22 are provided with latch springs 25 similar to the latch springs 7 carried by the supporting frame 3. It will be understood 40 that these springs automatically assume their outward position to prevent the downward movement of the supporting frames by which they are carried when said frames 45 are brought to their uppermost positions. When it is desired to allow the supporting frames to descend and carry the mirror frames into the pockets provided therefor, the latch springs are pressed against the

arms to which they are secured, to allow 50 said arms to descend.

Secured along the upper edge of the mirror carrying member 18 and upon the inner face thereof is the shelf carrying strip 26 to the lower edge of which is hinged the 55 shelf 27 which is adapted to be supported in a horizontal position by the supporting arm 28, the upper end of which is pivoted to the shelf 27 while the lower end is adapted for engagement against the stop 29 60 carried by the member 18. When the bracket 17 and mirror carrying member 18 are to be placed between the standards 13 and 14 and beneath the connecting board 15, the lower end of the supporting arm 28 65 is disengaged from the stop 29 to allow said arm and shelf 27 to drop against the member 18 and depend from the shelf carrying strip 26.

It will thus be seen that I have provided 70 a chair which may be readily converted into either a parlor chair or a hair dressing chair and one of such construction as to present a neat appearance at all times. It will also be apparent that this chair is of 75 strong and durable construction and may be employed for various purposes such as a reading chair, a reclining chair, etc.

What I claim is:—

1. A chair comprising a seat, back and 80 arms, a mirror carrying member connected to one arm and adapted to be folded into the same to form a part of said arm, and means for supporting the mirror carrying member.

2. A chair comprising a seat, arms and back, a mirror carrying member connected to one of said arms and adapted to be swung to a position opposite the back, a mirror for said mirror carrying member 90 and a shelf carried by said member.

In testimony whereof I have signed my name to this specification in the presence of two subscribing witnesses.

JAMES A. W. SEARS.
